(57) **CLAIM**

The ornamental design for a smart furniture control box, as shown and described.

DESCRIPTION

FIG. 1 is a top plan view of an embodiment of a smart furniture control box showing my new design with connection cover fully open;

FIG. 2 is a front elevational view of the smart furniture control box with connection cover fully open;

FIG. 3 is a front view of the smart furniture control box with connection cover fully open;

FIG. 4 is a back view of the smart furniture control box with connection cover fully open;

FIG. 5 is a bottom plan view of the smart furniture control box;

FIG. 6 is a right side view of the smart furniture control box with connection cover fully open;

FIG. 7 is a left side view of the smart furniture control box with connection cover fully open;

FIG. 8 is a bottom elevational view of the smart furniture control box;

FIG. 9 is a front elevational view of the smart furniture control box with connection cover partially open;

FIG. 10 is a front elevational view of the smart furniture control box with connection cover closed;

FIG. 11 is a top plan view of the smart furniture control box with function indicators and connection cover fully open;

FIG. 12 is a front elevational view of the smart furniture control box with function indicators and connection cover fully open;

FIG. 13 is a front elevational view of the smart furniture control box with function indicators and connection cover partially open; and,

FIG. 14 is a front elevational view of the smart furniture control box with function indicators and connection cover closed.

The broken lines shown in the drawing views are for illustrative purposes only and forms no part of the claimed design.
